UNITED STATES PATENT OFFICE.

WILLIAM BREWSTER, OF NEW YORK, N. Y.

DOOR STRUCTURE FOR CLOSED AUTOMOBILE BODIES.

Application filed May 24, 1924. Serial No. 715,501.

To all whom it may concern:

Be it known that I, WILLIAM BREWSTER, a citizen of the United States, residing at the city of New York, county of New York, 5 and State of New York, have invented certain new and useful Improvements in Door Structures for Closed Automobile Bodies; and I do declare the following to be a full, clear, and exact description of the 10 invention, such as will enable others skilled in the art to which it appertains to make and use the same.

This invention relates to window construction of the doors of closed automobiles, 15 with especial reference to the doors that are adjacent the rear mud guards, and has for its main object the lowering of the glass panes in the window openings of these doors so that such panes will not project 20 above the sill of the window casing.

In certain automobile bodies, the lower rear corner of the door is cut away so as not to interfere with the rear mud guard, and the consequence is that the well for the 25 glass pane in the door cannot extend deep enough so that the pane can be completely lowered to a plane at or below the level of the window sill.

Therefore, when in its lowest position in 30 the door, the glass pane would project several inches above the window sill which was annoying, unsightly and a source of actual danger in the event of an accident.

The present invention completely does 35 away with these disadvantages in a very simple and effective manner which will be readily understood from the following description in connection with the drawings which are filed herewith, and in which—

40 Figure 1 is a broken side elevation of a car body as it appears when equipped with the improvement with the glass pane elevated—

Figure 2 is a view similar to Figure 1 45 but broken away to show the construction of the rear well or guide way for the glass pane—

Figure 3 is a sectional elevation showing the glass pane fully lowered and the filler 50 block permanently in position—

Figure 4 is a detail elevation of the improved glass pane—

Figure 5 is a detail perspective view of the fixed filler block—

55 Figure 6 is a detail broken sectional elevation illustrating a pivoted and spring

actuated filler block, with the various parts in the position assumed when the glass pane is fully elevated—

Figure 7 is a view similar to Figure 6 60 but showing the position assumed by the several parts during the lowering of the glass pane—

Figure 8 is a detail perspective view of the form of filler block shown at Figures 65 6 and 7, and

Figures 9 and 10 are sectional elevations similar to Figures 6 and 7, but showing slight modifications of the manner of pivoting the filler block. 70

Similar numerals of reference denote like parts in the several figures of the drawing.

1 denotes a closed automobile body, 2 the rear mud guard, and 3 the door whose lower rear corner is cut away at 4 in general conformity with the shape of the mud guard. 75

The window opening in the door is designated by the numeral 5, and 6 is the glass pane therein.

7 is the rear guide wall in the well 8, 80 within which the pane 6 is lowered, and it will be readily seen that this groove 7 could not be extended far enough down to permit the glass pane to be fully lowered.

Therefore, the lower portion of this 85 groove 7 is deflected forwardly and downwardly as indicated at 9, while the lower rear corner of the glass pane is entirely cut away as noted at 10, so that it will be clear that the glass pane can be lowered so that 90 its upper edge will be at or below the level of the window sill, as shown at Figure 3.

When the glass pane is elevated the cutting away of the lower rear corner would produce an unsightly effect and would, 95 moreover, cause annoyance to the occupant of the car by providing an inlet for dust and the elements.

Therefore, a filler block 11 is permanently 100 fixed in the lower rear corner of the window opening, and this block has spaced side walls 12 which embrace the glass pane on both faces, and will completely conceal the cut away portion of the glass when the latter is in elevated position. 105

But, in the event that the presence of a permanent filler block 11 is objectionable, this block may be pivoted either to the door structure or to the glass itself, and may be provided with a spring element, and so associated with the glass pane that when the latter is lowered this block will automatically 110

disappear and when the glass is elevated the block will be automatically forced by a spring action into the position occupied by the block in Figure 1, so as to entirely conceal the cut away portion of the glass pane, and, although the permanent fixing of the block is preferred there has been shown in Figures 6 to 10 inclusive an arrangement of this block so that it would operate automatically in the manner before noted, and this will now be described.

Referring particularly to Figures 6, 7, and 8, the block is provided with parallel hinge eyes 13 and is pivoted within a recess 14 in the door structure by means of any suitable pin 15, the glass pane being embraced by the spaced side walls 12 of the block, the lower edge of the pane resting against the floor 17 of the block.

20 A coil spring 18 surrounds the pin 15 between the eyes 13, the ends of the spring being extended with one end bearing against the wall of the recess 14 and the other end bearing against the bottom of the floor 17, so that it will be clear that the downward swinging of this block is effected against the resiliency of the spring element.

When the window pane is lowered it will swing the block downwardly so that the floor 30 of the block will be housed within the recess 14, while no portion of the block will extend above the sill of the window opening, as clearly shown at Figure 7, and when the glass pane is elevated the spring element will 35 cause the block to be swung upwardly into the position shown at Figure 6 where such block will completely conceal the cut away portion 10 of the glass pane.

40 Instead of pivoting the block within the door structure it may be pivoted at 19 directly to the lower edge of the glass pane as shown in Figures 9 and 10, and a coil spring

20 disposed around a stud 21 secured to the spaced side walls of the block, the extremities of the spring being extended, one extremity bearing against the floor of the block, while the other extremity bears against the cut away portion of the window pane, so that when the pane is lowered the floor of the block will strike against the deflected portion 9 and will conform closely thereto so as not to interfere with the complete lowering of the pane as particularly noted at Figure 10. When the pane is elevated the block will, owing to the action of 55 the spring, automatically assume the position shown at Figure 9 so as to completely conceal the cut away portion of the glass pane.

What is claimed is:—

1. A drop window for the rear doors of closed automobile bodies, comprising a window well having the lower end of its rear window groove disposed forwardly and downwardly, a glass pane capable of sliding within said well and having its lower rear corner cut away, whereby the downward sliding movement of said pane is lengthened, and a filler block located at the rear lower corner of the window opening 70 and embracing said pane whereby said cut away portion of the pane is housed and concealed at both sides when said pane is fully raised.

2. A construction as specified in claim 1, 75 in which the filler means consists of a pivoted block that is carried into concealment by the downward movement of the pane with a spring for throwing the block in effective position when the pane is fully elevated.

In testimony whereof I affix my signature hereto.

WILLIAM BREWSTER.
